(57) **CLAIM**

The ornamental design for a rear compartment and rear panel of a car, as shown and described.

DESCRIPTION

The entire disclosure of U.S. application Ser. No. 29/606,194 filed on Jun. 2, 2017 is incorporated herein by reference. FIG. 1 is a front perspective view of the rear compartment and rear panel of a car showing my design thereof;

FIG. 2 is a rear view thereof; and,

FIG. 3 is a top plan view thereof.

Portions of the car shown in broken lines form no part of the claimed design.

1 Claim, 3 Drawing Sheets

FIG. 1

FIG. 2

FIG. 3
